WIRELESSLY OPERATED ELECTRICAL DECORATIVE LIGHT

Harry F. Waters, New York, N. Y.

Application February 10, 1937, Serial No. 125,111

12 Claims. (Cl. 240—10)

The present invention relates to wirelessly operated electrical decorative lamps, and, more particularly, to wirelessly operated decorative lamps for Christmas trees.

Heretofore, it was customary to employ candles or small incandescent lamps on Christmas trees for decorative purposes. Candles had the obvious disadvantage of providing a substantial fire hazard and in addition had to be replaced quite frequently. Small incandescent lamps did not completely solve the problem because they provided a light effect which was much too strong and could not imitate the soft and attractive glow of candles. Another grave objection against conventional incandescent lamps was that they had to be connected to a wire line carried throughout the tree and which interfered with the decorative value of the tree. The lamps and their sockets with the associated wires or cords have been quite heavy and weighed down the branches of the tree. Moreover, short circuits have frequently been caused by small threads or particles of tinsel or of tinfoil, which are extensively used on trees for decorative purposes, contacting parts of the lamp sockets or the protruding part of the lamp bases and cases have been known when serious fires involving loss of property or human life occurred for this reason. Although this situation was well known in the art for a considerable length of time and various suggestions and proposals have been made to solve the outstanding problem, none, as far as I am aware, of these various suggestions and proposals was completely satisfactory and successful.

I have discovered that the problem may be solved in a remarkably simple manner.

It is an object of the present invention to provide an improved system of electrical illumination for decorative purposes, particularly for Christmas trees, which is completely free from the disadvantages and inconveniences of conventional candles and of electrical incandescent lamps.

It is another object of the present invention to provide a device for operating electrical lamps or discharge tubes emitting light and mounted on a Christmas tree without connecting said lamps or tubes by wire to the source of electrical energy.

It is a further object of the invention to provide a device adapted to convert industrial electrical currents into high frequency currents, which is capable of energizing suitable light-emitting lamps by means of electrical currents

transmitted through the medium of a Christmas tree but without any direct wire connection.

Still another object of the invention is to provide a self-contained converter of industrial alternating currents to high frequency currents and having means for receiving and holding a Christmas tree exposed to the effect of such currents whereby discharge tubes and electrical lamps are actuated merely by means of the current received through the trunk and the branches of the Christmas tree.

The invention also contemplates discharge lamps of novel form and character capable of emitting an attractive, inspiring and soft-glowing light when employed in connection with the frequency converter of the present invention.

It is also within contemplation of the invention to provide a simple and self-contained frequency converting device of small dimensions for wirelessly operating decorative lights on Christmas trees, which is simple in construction and which may be manufactured and sold at a relatively low price.

Other and further objects and advantages will become apparent from the following description taken in conjunction with the accompanying drawing, in which:—

Fig. 1 illustrates a perspective view of a device embodying the principles of the present invention and holding a Christmas tree having wirelessly operated decorative lamps mounted thereon;

Fig. 2 depicts the electrical circuit employed in the device shown in Fig. 1;

Fig. 3 shows a discharge lamp of elongated form adapted to be wirelessly energized by means of the device of Fig. 1;

Fig. 4 is a modified gas discharge device of spherical form adapted to emit light under the influence of high frequency currents; and

Fig. 5 is a further modified gas discharge device having the form of a cross.

Broadly stated, according to the principles of my invention, I provide an oscillation producer adapted to produce electrical oscillations of a high frequency. The oscillation producers may be of widely different character such as a thermionic tube oscillator or an oscillator of the spark gap type, such as employed in conventional medical diathermy machines. I introduce one pole of the produced high frequency currents into a Christmas tree while the other pole of the oscillation producer may remain disconnected or, if desired, may be grounded. As decorative lamps, I employ small evacuated vessels of glass in various decorative forms and

shapes with or without internal electrodes, which are in unipolar electrical connection with the trunk or with the branches of a Christmas tree. These small glass vessels are filled with a suitable 5 gas or mixture of gases at a low pressure, such as, for example, neon, argon, helium, hydrogen, nitrogen, etc. As those skilled in the art know, evacuated vessels of the described character will emit a soft glow or light when subjected to the 10 effect of high frequency currents or fields, due to the ionization of the gas content. The color and the character of the light emitted largely depends on the character and pressure of the gases contained within the vessel or glass envelope, the frequency and the character of the 15 high frequency currents, and on the form and shape of the electrodes. Discharge lamps of the described character will emit light even in the case when they are connected only to one side 20 of a high frequency oscillatory circuit, and, in case the high frequency field is sufficiently strong, even without any wire or electrical connection whatsoever. Discharge vessels of this type are very moderate in their current requirements so 25 that an oscillator of relatively small output may supply a relatively large number of such lamps with high frequency currents. In addition to this, high frequency currents within the frequency range contemplated have no physiological 30 effect on the human body so that they are harmless and cannot produce direct shocks even if the conductors are touched directly.

Referring now more particularly to Fig. 1 of the drawing, a preferred embodiment of the invention is illustrated. A box or casing 1 constituted of wood or some similar material is supported on feet 2 constituted of a good insulator such as, for example, hard rubber, synthetic resins, etc. Casing 1 is provided with a tree-supporting member 3 constituted of metal mounted on the top surface thereof, having a tubular extension adapted to receive and to hold a Christmas tree. A thumb screw 4 may be provided in the tree supporting member for securely holding the tree in position and also for providing a good electrical connection between the member and the tree. Within casing 1 is provided a small oscillator preferably of the thermionic tube type adapted to convert the alternating current from the power line and introduced into the casing through cord and plug 9, into a high frequency current. The one side of the output of the high frequency oscillator is connected to the tree supporting member 3, while the other side of the output is grounded through a wire 10. On the branches of tree 5 are mounted or suspended light-emitting gas discharge tubes 6, 7 and 8 having various decorative forms, which are in electrical connection with 60 the tree through little hooks, wires, or clamps having at the same time the object of holding them in position on the tree.

From the preceding description the operation of my device for wirelessly operating decorative lamps on Christmas trees will be readily understood by those skilled in the art. When casing 1 is connected to the power line, the oscillator therein will produce electrical oscillations of a high frequency which are unipolarly introduced 70 into the tree. It is to be noted that a tree which still contains some natural moisture, is a fairly good conductor of high frequency electrical energy. Thus, the high frequency energy will be transmitted through the medium of the tree to 75 the various decorative lamps in the form of gas

discharge vessels which will light up under the influence of the high frequency currents communicated thereto. The unipolar connection of the discharge lamps with the oscillator through the tree will be sufficient for providing a displacement current in the lamps in case the frequency of the high frequency current is high enough. Preferably, frequencies considerably below the radio broadcasting range are used corresponding to wave lengths between 100 meters 10 and 6 meters to prevent interference with conventional broadcasting receivers.

Fig. 2 is a preferred circuit diagram for the conversion of industrial alternating currents into the high frequency currents required for the 15 wireless operation of decorative lights. A transformer having a primary winding 11 and three secondary windings 12, 13, and 14, is provided for supplying a conventional full wave rectifier tube 15 with filament and plate current, and an 20 oscillator tube 21 with filament heating current. The rectified current is filtered by means of low frequency chokes 16 and 17 and filter condensers 19 and 20 and is hereafter introduced through a high frequency choke 18 into the oscillator proper. The oscillator comprises tube 21, tapped inductance 22, blocking condenser 23 and grid condenser and resistance 24 and 25, respectively, which are connected to the tube in conventional manner. The high frequency oscillations produced in the circuit are taken off by means of a coil or inductance 26 loosely coupled with inductance 22 and tuned by a variable series condenser 27. The output of high frequency oscillations is connected to the tree supporting member and to the ground. In view of the fact that this circuit is of conventional character and is well known to those skilled in the art, its operation and the production of electrical oscillations thereby will be readily understood by those 40 skilled in the art without any further explanation.

Fig. 3 illustrates a preferred and exemplary form of a lamp to be employed in connection with the device embodying the principles of the present invention. Essentially, the lamp comprises a sealed glass envelope 31 of cylindrical shape having a base 33 and a clamping member 34 associated therewith which permits to readily attach the lamp to one of the branches of the Christmas tree. If desired, the lamp may be provided with a single internal electrode 32 which is carried through the sealed glass envelope and is electrically connected to the clamping member 34. In most cases, however, it is not necessary 55 to provide an internal electrode but only an external electrode, for example, by making base 33 of metal. In both cases, when the lamp is attached to one of the branches of the Christmas tree by means of the clamping member, and the tree is energized by means of the oscillator, the glass envelope 31 will be filled with a soft glow in accordance with the character and pressure of the gas within. In case an electrode is provided, it will be covered with a glow discharge and will 60 provide in both cases an attractive and inspiring decorative effect.

Fig. 4 depicts a modified embodiment of a gas discharge device adapted to be operated by high frequency electrical currents. The lamp comprises a sealed glass vessel of spherical form, 41, filled with a suitable gas at a low pressure. Glass vessel 41 is provided with an external electrode 42 which is secured to the upper portion of the spherical vessel by means of cementing. A short 75

and flexible wire 43 soldered to the external electrode 42 permits to readily secure the sphere to a branch of the tree, for example by winding the wire around the branch a few times. This at the same time will provide the required electrical connection between the tree and the discharge lamp. If desired, spherical glass vessel 41 may be constituted of colored or of painted glass in order to obtain novel and attractive decorative effects.

Fig. 5 shows a further modified embodiment of a lamp having a glass vessel in the form of a cross, 51, an internal electrode 52, a base 53 which is preferably constituted of metal and a clamp or fastening device 54. In view of the similarity of construction, operation of this modified embodiment will be readily understood by those skilled in the art without any further explanation.

It is to be noted that the device embodying the principles of the present invention provides a number of important advantages. First of all, a device for wirelessly operating decorative lamps on Christmas trees and similar objects, is provided which does not require any wire connection between the source of electrical energy and the lamps but relies merely on the transfer of electrical energy by means of radiation and by means of unipolar conduction through the medium of the tree. This circumstance not only permits complete freedom in the arrangement of the decorations on the tree, but also eliminates bulky, unsightly and dangerous wire connections.

It is also to be observed that the gas discharge lamps operated by the device of the invention provide novel and highly attractive decorative and light effects which are by far superior to the strong glare of conventional incandescent lamps and which provide a soft and pleasing glow in keeping with the spirit of Christmas.

Moreover, the device embodying the invention completely eliminates the danger of short circuits or of shocks in view of the fact that the high frequency currents employed have no physiological effect and are completely harmless.

Furthermore, the device embodying the invention is extremely simple in construction and to operate and may be manufactured and sold at a low price, particularly in view of the fact that the gas discharge lamps contemplated consume very small quantities of electrical energy so that a relatively small output of oscillatory energy will satisfactorily operate a large number of lamps.

Although the present invention has been described in connection with a few preferred embodiments thereof, and particularly as applied to a Christmas tree, variations and modifications may be resorted to without departing from the principles of the present invention. I consider all of these variations and modifications as within the true spirit and scope of the present invention, as disclosed in the present description and defined by the appended claims.

I claim:—

1. In a device of the character described, the combination comprising means for varying electrical energy at a high frequency rate, means for supporting a Christmas tree, means for impressing said energy on said tree, and electrical light producing means associated with said tree and adapted to emit light under the effect of such energy.

2. In a device of the character described, the combination comprising means for converting an electrical current of low frequency into electrical

oscillations of high frequency means for supporting a Christmas tree, coupling means for introducing said oscillations into said tree, and electrical lamps mounted on said tree and adapted to emit light under the effect of such oscillations. 5

3. In a device of the character described, the combination comprising means for converting an alternating current of an industrial frequency into electrical oscillations of high frequency, means for supporting a Christmas tree, means 10 electrically associated with said supporting means for unipolarly introducing said oscillations into said Christmas tree, and electrical discharge lamps mounted on said tree and unipolarly connected thereto, said lamps being adapted to emit 15 light under the influence of said oscillations.

4. In a device of the character described, the combination comprising a high frequency oscillator, means for supplying electrical power to said oscillator, means for withdrawing high frequency oscillations therefrom, supporting means connected to one pole of the output of said oscillator for holding a Christmas tree, and a plurality of sealed glass vessels containing gas at reduced pressure mounted on said tree and adapted to 25 emit light when said oscillator is actuated.

5. In a device of the character described, the combination comprising a source of current, an oscillator connected to said source of current and adapted to produce electrical oscillations of high 30 frequency, metallic supporting means for a Christmas tree electrically connected to one pole of said oscillator, a ground lead connected to the other pole of said oscillator, and a plurality of glass vessels containing gas at a low pressure 35 mounted on said tree and unipolarly energized by high frequency oscillations transmitted through the medium of said tree.

6. In a device of the character described, a casing, a high frequency oscillator in said casing, 40 means for supplying electric power to said oscillator, a metallic tree-supporting member mounted on said casing and connected to said oscillator, said supporting member being adapted to receive and to hold a Christmas tree and to transfer 45 high frequency oscillations thereto, and a plurality of electric discharge tubes on said tree energized by said oscillations unipolarly transmitted through the medium of said tree.

7. In a device of the character described, the 50 combination comprising a casing, means for insulating said casing from a supporting surface, a high frequency thermionic tube oscillator in said casing, a cord for supplying electrical energy to said oscillator from a power line, a tree-supporting member of conductive material mounted on said casing and connected to said oscillator, said supporting member being adapted to receive and to hold a Christmas tree and to transfer high 55 frequency oscillations thereto. 60

8. In a device of the character described, the combination comprising a casing, a plurality of insulative feet for supporting said casing, a high frequency oscillator in said casing, a cord for supplying electrical energy to said oscillator from 65 a power line, a tree supporting member constituted of a metallic material mounted on the top panel of said casing and electrically connected to one pole of the output of said oscillator, said supporting member being adapted to support a 70 Christmas tree and to transfer electrical oscillations thereto, a ground lead connected to the other pole of the output of said oscillator, and electrical discharge tubes mounted on said tree and unipolarly energized by high frequency 75

energy transmitted through the trunk and the branches of said tree.

9. In a system of wirelessly operating electrical decorative lights on a tree, the combination comprising a casing, a high frequency oscillator in said casing, means for supplying electric power to said oscillator, tree-supporting means mounted on said casing, and coupling means electrically associated with said oscillator and said supporting means and adapted to transfer high frequency oscillations to said tree.

10. In a system of wirelessly operating electrical decorative lights on a tree, the combination comprising a casing, a high frequency oscillator in said casing, means for supplying electrical energy to said oscillator from a power line, tree-supporting means mounted on said casing and electrically associated with said oscillator, said supporting means being adapted to receive and to hold a Christmas tree and to transfer high frequency oscillations thereto.

11. In a system of wirelessly operating elec-

trical decorative lights on a tree, the combination comprising a casing, a high frequency oscillator in said casing, means for supplying electrical energy to said oscillator from a power line, tree-supporting means adapted to receive a Christmas tree and to insulatedly hold the same from the ground, and coupling means electrically associated with said oscillator and said supporting means to transfer high frequency oscillations to said tree.

12. In a system of wirelessly operating electrical decorative lights on a tree, the combination comprising a high frequency oscillator, means for supplying electrical energy to said oscillator from a power line, tree-supporting means adapted to receive and to insulatedly hold a Christmas tree from the ground, and coupling means electrically associated with said oscillator and said supporting means to transfer high frequency oscillations to said tree.

HARRY F. WATERS.
